UNITED STATES PATENT OFFICE.

HERMAN PETERS, OF MILWAUKEE, WISCONSIN, ASSIGNOR TO HOLEPROOF HOSIERY CO., OF MILWAUKEE, WISCONSIN, A CORPORATION OF WISCONSIN.

KNITTING-MACHINE

1,240,250.

Specification of Letters Patent. Patented Sept. 18, 1917.

Application filed June 10, 1915. Serial No. 33,289.

To all whom it may concern:

Be it known that I, HERMAN PETERS, a citizen of the United States, residing at Milwaukee, in the county of Milwaukee and State of Wisconsin, have invented certain new and useful Improvements in Knitting-Machines, of which the following is a specification, reference being had to the accompanying drawing, forming a part thereof.

10 This invention relates more particularly to circular-latch needle knitting machines and to mechanism for reinforcing certain parts of tubular knitting produced on such machines.

15 Its main objects are to avoid floating the reinforcing yarn across the plain or unreinforced parts of the knitted fabric, and the trouble and waste incident to trimming or cutting away the surplus floating yarn by hand or otherwise, and generally to improve the construction and operation of machines of this class.

It consists in the construction, arrangement and combination of parts as hereinabove particularly described and pointed out in the claims.

In the accompanying drawing like characters designate the same parts in the several figures.

30 Figure 1 is a side elevation of a circular knitting machine embodying the invention; Fig. 2 is a planiview on an enlarged scale of the knitting head of the machine; Fig. 3 is an enlarged rear elevation as viewed from the left relative to Fig. 1; Fig. 4 is a detached detail view of a tension releasing device constituting a part of the invention; Fig. 5 is a vertical section on the line 5—5, Fig. 2, of the upper part of the machine; Fig. 6 is a vertical section on the line 6—6, Fig. 2; and Figs. 7, 8 and 9 are detached detail views of the inside cutting, holding and guiding devices of the reinforcing mechanisms, Figs. 7 and 9 being elevations as viewed from the lower side of Fig. 2, showing the parts in different positions, and Fig. 8 being an elevation and partial section as viewed from the left relative to Fig. 2.

The machine to which the present invention is applied comprises a rotary needle cylinder 1, provided with a circular series of latch needles 2, a latch ring 3, a sinker ring 4, a needle carrying ring 5, and yarn carriers 6, 7, 8 and 9, pivoted on a cross pin 10 in an extension on one side of the latch ring 3.

The springs 11, pressing against the heels or outer ends of the yarn carriers, tend to force their inner ends through which the several yarns used in the machine are guided, downward into working position against the bed 60 or stop 12, shown in Fig. 6. The yarn carriers are turned upwardly out of working position against the tension of the springs 11 by lifting jacks or levers 13, which are actuated in the usual manner in a machine 65 of this kind, by cams (not shown) on a shaft 14, shown in Fig. 1, one of the lifting jacks or levers being shown in Fig. 6 in connection with the reinforcing yarn carrier 6. In the present machine the carrier 9 is employed to 70 guide the main yarn which is knit continuously into the entire fabric, while the remaining carriers 7 and 8, or either of them, are or may be used for supplying one or more yarns either continuously or intermittently, to the needles, for various kinds of knitting.

As usual in machines of this kind, the lifting jack or lever 13, which coöperates with the carrier 6 for the reinforcing yarn, designated *a* on the drawing, has two actuating connections, one with a cam on the shaft 14, and the other with a cam (not shown) on the shaft 15, shown in Fig. 1, the latter cam serving to actuate the yarn carrier during the reinforcing operations of the machine, while the former cam serves to lift and hold the carrier in a still higher position, indicated by dotted lines in Fig. 6, while plain or unreinforced portions of the 90 fabric are being knit.

The machine is provided as shown in Figs. 2 and 5 with a tension device comprising two disks or jaws 16, between which the reinforcing yarn *a*, is led to the carrier 6, 95 and which are yieldingly pressed together by a spring 17.

The reinforcing yarn passes through and is directed in proper position to the tension device by guides 18 and 19.

The parts thus far described are generally of the usual wellknown construction and arrangement in circular knitting machines of the type to which the present invention is applicable. In connection with such parts the reinforcing mechanism constituting the invention comprises, as shown in Figs. 2, 5, 7, 8 and 9, a reciprocating slide 20, formed or provided at one end adjacent to the circular series of needles on the inner side 110

thereof, with a downwardly directed hook, a cutter 21, coöperating with one side of the hook to sever the reinforcing yarn *a* near the point in the fabric from which it is withdrawn, and a yielding clamp 22, coöperating with the other side of the hook to grip and hold the severed or detached end of the yarn when the carrier 6 is shifted upwardly out of working position, as shown by full lines 5 in Fig. 6. This slide, cutter and clamp are mounted on a segmental plate 23, which is supported within the series of needles just above the needle cylinder 1, by an angular arm 24, which is fastened at one end to the 10 rear side of the latch ring 3. The cutter blade 21 is adjustably and detachably fastened to the edge of the plate 23, or a section thereof, approximately parallel with and close to the series of needles on the opposite 15 side of the hook slide 20 from, and a short distance in advance of the carrier 6 relative to the direction of rotation of the needle cylinder and needles as indicated by an arrow in Fig. 2.

25 As shown in Fig. 8, the clamp 22 is provided with a stem which is guided in a socket formed therefor in the plate 23 at right angles to the hook slide 20, and a spiral spring inserted in an enlargement of 30 said socket, presses and holds the clamp 35 yieldingly against said slide.

A reciprocating movement is imparted to the hook slide 20 during the reinforcing operation of the machine by the following 40 means:

A U-shaped lever fulcrumed on the plate 23 by a pin or bolt 25 passing vertically through a tubular connecting member of the lever and fastened at its lower end in the 45 plate, has two horizontally disposed arms 26 and 27, one above the other. The arm 27 engages with a notch in the upper side of the hook slide 20, as indicated by dotted lines in Fig. 2. The upper arm 26 is connected, as shown in Figs. 2 and 3, by a link 28 with the upper end of a vertically disposed lever 29, which is fulcrumed between its ends on the outer side of the latch ring 3. The lower end of the lever 29 is provided 50 with a roller 30, arranged to coöperate with a cam 31 attached to and rotatable with the sinker bed surrounding the needle cylinder 1, below the sinker ring 4. A spring 32 coiled around the fulcrum bearing of the 55 lever 29 and connected at one end with said bearing and at the other end with an arm 33 on the fulcrum pin or journal of the lever, tends to turn the lever arm 26 outwardly and to hold the roller 30 in working 60 relation to the cam 31. The inward movement of the upper end of the lever 29 toward the needle cylinder is limited, and overthrow by momentum of the parts connected therewith is prevented by an adjustable stop 34, while the movement of said 65

lever in the opposite direction is limited by an adjustable stop 35.

A bell crank lever 36, fulcrumed on the plate 23, has one of its arms pivotally connected with a lateral extension of the lower lever arm 27, and its other arm, which extends outwardly between the lever arms 26 and 27, formed or provided at the end with a downwardly directed hook or projection 37, serving as an inside guide for the reinforcing yarn *a*, and coöperating with the carrier 6 to direct said yarn with certainty between the same two needles in successive revolutions of the needle cylinder when the carrier is lowered into working position during the operation of the reinforcing mechanism.

The hooked guide arm of the lever 36 is adapted to oscillate between the hook slide 20 and a point directly opposite the yarn 35 carrier 6, as shown in Figs. 2 and 6.

For separating the disks or jaws 16 of the tension device and relieving the reinforcing yarn *a* from tension while it is being knit into the fabric, an angular lever 38, fulcrumed on one side of an overhanging arm 39 which carries the tension device, is adapted by engagement with the stem of the movable disk or jaw, to separate the disks or jaws in opposition to the spring 40, which is held by a retracting spring 41 in engagement with the heel 90 or outer end of the carrier 6, as shown in 95 Figs. 2 and 3.

To delay the separation of the jaws 16 and removal of tension on the reinforcing 100 yarn *a* after the carrier 6 has been lowered into working position and until the yarn adjacent to its detached end held by the 105 clamp 22, is secured in the fabric by a number of stitches, the longer arm of the lever 38 is jointed, as shown in Figs. 3 and 4, and its pivoted end section is adapted to yield upwardly against the tension of a spring 42, as shown in Fig. 4.

The spring 42 normally holds the sections of the jointed lever arm in alignment with each other, as shown in Fig. 3.

The link 28 is formed or provided with an upward projection 43, which by engagement with a laterally projecting pin or lug 44 on the pivoted section of the lever 38, serves as a stop to limit the downward movement of said section and prevent its engagement with the stem of the movable jaw 16 until said projection 43 has been 120 shifted with the link 28 outwardly far enough to release the pin or lug 44, whereupon the spring 42 throws the pivoted section 125 down into engagement with the movable jaw, as indicated by dotted lines in 130

Fig. 4, thereby separating it from the other jaw, the end of the stem being rounded and the side of the pivoted section rounded or beveled, as shown in Fig. 5, for this purpose.

When the reinforcing mechanism operating on the yarn *a* is thrown out of action and the carrier 6 is shifted into and held in its uppermost position, indicated by the 10 upper dotted lines in Fig. 6, by a cam on the shaft 14, as hereinbefore mentioned, the yarn is drawn by the rotary motion of the cylinder into engagement with an inside clamp or holder, and is severed by a cutter 15 (not shown) with which machines of this kind are ordinarily provided for holding and severing yarns which are used in parts only of the entire fabric.

To prevent the operation of the hook 20 slide 20 and inside guide 37 by the cam 31 and to hold them out of the way in the positions in which they are shown by full lines in Fig. 2, the machine is provided, as shown in Figs. 2 and 3, with a spring actuated 25 hook or deterrent 45, which is pivotally mounted on the latch ring 3, and is adapted when released to engage with the arm 33 and lock and hold the lever 29 with the hook slide 20 and the guide 37 connected therewith, 30 in the positions in which they are shown in Figs. 2 and 3, and in which they are unaffected by the cam 31.

The deterrent 45 is disengaged from the arm 33 when the reinforcing mechanism is 35 to be brought into action, and is released to engage with said arm when said mechanism is to be thrown out of action, by a cam 46 on the shaft 14, which engages with one end of a lever 47, as shown in Fig. 1. 40 With the opposite end of the lever 47 a rod 48 is pivotally connected. This rod, extending upwardly from said lever, is guided in the base of the knitting head or a part of the frame, and is provided at its 45 upper end, as shown in Figs. 2 and 3, with a laterally projecting arm 49, which is adapted by engagement with a pin or lug 50, projecting from one side of the deterrent 45, to lift and hold said deterrent out of engagement with the arm 33 when the rod 48 is moved upwardly. A spring 51, surrounding the rod between the base of the knitting head or part of the frame in which the rod is guided and a shoulder or washer 55 52 on the rod, tends to lift and hold the deterrent 45 out of engagement with the arm 33 and to hold the lever 47 in engagement with the periphery of the cam 46, as shown in Figs. 1 and 3.

60 In the operation of the machine, when the reinforcing mechanism is brought into action, the cam on the shaft 14, which normally holds the carrier 6 in its highest position, as indicated by the upper dotted lines 65 in Fig. 6, while the reinforcing mechanism

is inactive, releases said carrier, whereupon the cam on the shaft 15 becomes effective to alternately lift and lower the carrier to its middle position, as shown by full lines, and to its lowest position, as indicated by 70 the lower dotted lines in Fig. 6, through the medium of the lifting jack or lever 13, in the usual manner in a machine of this class.

At a certain point in the rotation of the 75 needle cylinder 1, the carrier 6 is shifted from its intermediate to its lowest position thereby carrying the yarn *a* down and with the aid of the inside guide 37 directing it between two needles, as indicated by dotted lines in Fig. 6. With the continued rotation of the needle cylinder the reinforcing yarn is knit with the main yarn into the fabric, in the usual manner, until at another point in the rotation of the needle cylinder, 80 determined by the shape of the cam on the shaft 15 which actuates the carrier during the reinforcing operation of the machine, the carrier is lifted into its intermediate position, thereby withdrawing the yarn *a* 85 upwardly out of range with the needles 2.

Before the carrier 6 is thus lifted to its intermediate position, the cam 31, or the high part thereof, clears the roller 30 on the lower end of the lever 29, thus permitting the spring 32 to turn the upper end of said lever outwardly against the back stop 35, and through the link 28 to turn the lever arms 26 and 27 outwardly. The hook slide 20 is thus thrust outward into the position shown in Fig. 7, and the inside guide 37 is turned forward toward said slide into the position indicated by dotted lines in Fig. 2.

As the fabric advances with the needle 105 cylinder, it draws the yarn *a*, from the elevated carrier 6, underneath and into the bight of the hook on the slide 20, and underneath the hooked end of the guide 37, as shown in Fig. 7. The cam 31 is thereupon 110 brought into engagement with the roller 30, and turns the upper end of the lever 29 inwardly into engagement with the front stop 34, thereby operating through the rod 28 and lever arms 26 and 27, to shift the hook 115 slide 20 back to its former position, as shown in Figs. 2, 8 and 9, and to swing the guide 37 backward into position opposite the carrier 6, as shown in Fig. 2.

As the hook on the slide 20 is withdrawn 120 carrying the yarn in its bight inwardly between the clamp 22 and the cutter blade 21, the yarn is first gripped between the clamp and one side of the hook, and while it is thus held it is carried by the hook against the 125 edge of the cutter blade on the opposite side thereof and is severed close to the fabric from which it is withdrawn, as shown in Figs. 2, 8 and 9.

The guide 37 moving backward to its 130

position opposite the carrier 6, as shown in Fig. 2, draws the yarn inwardly from the carrier directly across and above the path of the needles into position, as shown in Figs. 2 and 6, to be reinserted between the same two needles, when they are brought again by the rotation of the needle cylinder underneath the carrier and the carrier is lowered into working position, as indicated by dotted lines in Fig. 6. As the yarn is thus drawn downward between the needles by the carrier, it is withdrawn from the hooked end of the guide 37, and is knit into the fabric, a few stitches being formed before the jaws 16 of the tension device are separated, as hereinbefore described, and the end of the yarn is released by the hook slide 20 and the clamp 22.

Immediately following the lowering of the carrier 6 into working position, the cam 31 or the high part thereof, clears the roller 30, and the spring 32 turning the upper end of the lever 20 outward against the back stop 35, shifts the hook slide 20 outward into its receiving position shown in Fig. 7, and turns the guide 37 forward into the position indicated by dotted lines in Fig. 2, thereby releasing the end of the yarn *a* close to the fabric into which it is knit. The hook of the slide 20 and the guide 37 are left in the positions in which they are shown in Fig. 7, to receive the reinforcing yarn *a* when the carrier 6 is again lifted out of working position and the yarn is drawn forward with the advancing fabric from the elevated carrier.

The foregoing operations are automatically repeated for a number of courses, controlled by the cam on the shaft 14 hereinbefore mentioned which determines the number and extent of the reinforced portions of the fabric and the intervals between them lengthwise of the fabric until said cam lifts the carrier 6 to its highest position as indicated by the upper dotted lines in Fig. 6.

When a raised or higher part of the cam 46 is brought into engagement with the lever 47, a little in advance of the elevation of the carrier 6 to its highest position; the rod 48 is drawn downwardly against the tension of the spring 51, thereby releasing the detent 45, which is thereupon turned by its spring into engagement with the arm 33, locking and holding the lever 29 with the slide 20 and guide 37 in the positions in which they are shown in Figs. 2 and 3, until they are again released by the disengagement of the detent 45 from the arm 33, when the lever 47 drops into a low part of the cam 46 immediately following the movement of the carrier 6 from its highest to its lowest position.

When the reinforcing mechanism is thrown out of action, as hereinbefore explained, by the cam on the shaft 14, which

lifts the carrier 6 into its highest position, indicated by dotted lines in Fig. 6, and by the cam 46 which controls the operation of the hook slide 20 and guide 37, the reinforcing yarn *a* is carried forward with the fabric to which it is attached, until it is caught by the inside holder and severed by the cutter hereinbefore mentioned.

Various changes in the construction and arrangement of parts constituting the reinforcing mechanism and of the parts of the machine co-operating therewith, may be made without departing from the principle and scope of the invention as defined in the following claims.

I claim:

1. In a knitting machine the combination with a rotary needle cylinder provided with a circular series of latch needles, of a yarn carrier movable into and out of position to direct a reinforcing yarn to the needles between predetermined points in successive courses, means for operating said carrier, a reciprocating hook movable transversely to the course of knitting within the series of needles and adapted when projected outwardly toward the needles to receive into its bight the yarn drawn by the fabric from the carrier as the carrier is shifted out of working position, a yielding clamp co-operating with one side of the hook as it is withdrawn inwardly to first grip the yarn, and a stationary cutter co-operating with the other side of the hook to then sever the yarn between the clamp and the fabric.

2. In a knitting machine the combination with a rotary needle cylinder provided with a circular series of latch needles, of a reinforcing yarn carrier, means for shifting said carrier into and out of working position at predetermined points in successive courses of knitting, a reciprocating hook located within and movable transversely to the series of needles and adapted when projected outwardly toward the needles to receive into its bight the yarn drawn from the carrier by the rotation of the cylinder with the fabric as the carrier is shifted out of working position, a laterally yielding clamp co-operating with one side of the hook to first grip the yarn, a stationary cutter co-operating with the other side of the hook to then sever the yarn close to the fabric, a reciprocating inside guide movable back and forth transversely to the movement of the hook and co-operating with the carrier when it is shifted into working position to direct the yarn between the same needles in successive courses of knitting, and means for operating said hook and guide.

3. In a knitting machine the combination with a needle cylinder provided with a series of needles, of a reinforcing yarn carrier, means for shifting said carrier into and out of working position at predetermined points

- in successive courses of knitting, a reciprocating hook located within and movable transversely to the series of needles and adapted when projected outwardly toward the needles to receive the yarn drawn from the carrier by the rotation of the fabric with the cylinder as the carrier is shifted out of working position, a clamp coöperating with one side of the hook to first grip the yarn, 5 a cutter coöperating with the other side of the hook to then sever the yarn close to the fabric, an inside guide movable into and out of position to coöperate with the carrier when it is shifted into working position, to direct the yarn between the same needles in successive courses of knitting, and means for operating said hook and guide.
4. In a knitting machine the combination with a rotary needle cylinder provided with 20 a circular series of latch needles, of a reinforcing yarn carrier, means for shifting said carrier into and out of working position at predetermined points in successive courses of knitting, means within the series of needles for severing the yarn close to the fabric when it is withdrawn by the carrier from the needles and for holding the detached end and returning the same to the needles when the carrier is shifted back to 25 working position, a tension device comprising two disks between which the yarn is constantly directed to the carrier, one of said disks being stationary and the other movable and provided with a stem which passes 30 through and is guided axially in the stationary disk, a spring tending to press the movable disk toward the stationary disk, and a tension releasing lever adapted by engagement with the end of the stem of the 35 movable disk to separate said disks and remove tension from the reinforcing yarn when said carrier is shifted into working position.
5. In a knitting machine having a needle cylinder provided with a circular series of needles, a reinforcing yarn carrier, means for shifting said carrier into and out of position to direct a reinforcing yarn to the needles between predetermined points in successive courses of knitting, the combination of means within the series of needles for severing the yarn when it is withdrawn by the carrier from the needles and for holding the detached end until the carrier is shifted 50 into working position, means for operating said severing and holding means, a tension device comprising separable jaws between which the yarn is led to the carrier, a backwardly yielding tension releasing arm operated by said carrier to separate said jaws, and a movable stop actuated with the yarn severing and holding means and adapted by engagement with said releasing arm to delay the separation of the tension jaws when 55 the carrier is shifted into working position 65 until said holding means releases the yarn.
6. In a knitting machine the combination with a needle cylinder provided with needles, a yarn carrier movable into and out of position to direct a reinforcing yarn to the needles between predetermined points in successive courses of knitting and means for operating said carrier, of a reciprocating hook located inside of the series of needles, a cutter coöperating with one side of the hook to sever said yarn, a yielding clamp coöperating with the other side of the hook to grasp and hold the detached end of the yarn when the carrier is shifted out of working position, a hook operating connection, a tension device comprising separable jaws between which the yarn is led to the carrier, a backwardly yielding tension releasing arm operated with the carrier to separate said jaws, and a stop on the hook operating connection adapted by engagement with said arm to delay the separation of the jaws when the carrier is shifted into working position until the hook is shifted to release the end of the yarn held thereby against the clamp. 70 75 80 85 90
7. In a knitting machine the combination with a rotary needle cylinder provided with a circular series of latch needles, a yarn carrier movable into and out of position to direct a reinforcing yarn to the needles between predetermined points in successive courses of knitting and means for operating said carrier, of a reciprocating hook located within the series of needles adjacent to the carrier, a clamp coöperating with one side of the hook to grip and hold the yarn when the carrier is shifted out of working position, a cutter coöperating with the other side of the hook to sever the yarn while it is held by the clamp, a cam connected and rotatable with the needle cylinder for operating said hook in timed relation to the operation of the carrier, and a cam adapted to prevent the operation of the hook by the first mentioned cam during the knitting of unreinforced portions of the fabric. 95 100 105 110
8. In a knitting machine the combination with a rotary needle cylinder provided with a circular series of latch needles, a yarn carrier movable into and out of position to direct a reinforcing yarn to the needles between predetermined points in successive courses of knitting and means for operating said carrier, of a reciprocating hook located inside of the series of needles, a yielding clamp coöperating with one side of the hook to grip and hold the yarn when the carrier is shifted out of working position, a cutter coöperating with the other side of the hook to sever the yarn while it is held by the clamp close to the fabric, a lever connected with said hook, a cam connected and rotatable with the needle cylinder and adapted 115 120 125

by engagement with said lever to shift said hook at predetermined points in successive courses of knitting, a spring tending to hold the lever in engagement with the cam, a 5 detent adapted by engagement with the lever to prevent the operation of the hook by the cam, and a releasing cam adapted to shift said detent for rendering the reinforcing mechanism active and inactive at prede-

termined times in the operation of the ma- 10 chine.

In witness whereof I hereto affix my signature in presence of two witnesses.

HERMAN PETERS.
